Term of patent 14 years

(Cl. D12—2)

FIG. 1.

FIG. 2.

FIG. 3.

FIG. 4.

FIGURE 1 is a plan view of the animal feeder, showing my new design;

FIGURE 2 is a side elevational view;

FIGURE 3 is a front elevational view; and

FIGURE 4 is a rear elevational view.

The undisclosed side of the animal feeder is substantially the same in appearance as the side shown.

The essential features of the design reside in the portions shown in full lines.

I claim:

The ornamental design for an animal feeder as shown and described.
